COUNTERPOISE

John V. Fill, Miami, Fla., assignor to the United States of America as represented by the Secretary of War

Application January 23, 1945, Serial No. 574,161

3 Claims. (Cl. 250—17)

(Granted under the act of March 3, 1883, as amended April 30, 1928; 370 O. G. 757)

1

The invention described herein may be manufactured and used by or for the Government for governmental purposes, without the payment to me of any royalty thereon.

My present invention relates to antenna counterpoise systems, and more particularly, to a combination parachute and counterpoise which, with a radio transmitter suspended therefrom, is adapted to be launched from an airplane.

While not limited thereto, my present invention is particularly well suited to use with the apparatus and in the manner described in the copending application of George F. Wright, entitled "Antennas," Serial No. 574,157, filed January 23, 1945, now abandoned.

It has heretofore been proposed to construct the shroud lines of a parachute of wire, so that they could serve the dual functions of supporting a radio transmitter as aforesaid, and provide a part of the antenna system therefor. However, it is found that such shroud lines stretch about 25% when the device is launched, as a result of which said lines snap. Furthermore, said lines tend to become tangled, and so interfere with the proper descent of the parachute.

Hence, it is the main object of my present invention to provide a combination parachute and counterpoise which obviates the foregoing disadvantages by so incorporating the wires of a counterpoise system in the shroud lines of a parachute as to permit said shroud lines to elongate, and absorb the shock resulting from the check on the descent of the equipment when the parachute opens, without the danger of snapping or entangling.

In the accompanying specification there is described, and in the annexed drawing shown, what is at present considered a preferred embodiment of the combination parachute and counterpoise of my present invention. It is, however, to be clearly understood that my present invention is not limited to said embodiment, inasmuch as changes therein may be made without the exercise of invention and within the true spirit and scope of the claims hereto appended.

In said drawing:

Figure 1 is a side elevational view of a parachute with a radio transmitter suspended therefrom, said parachute incorporating combined shroud lines and counterpoise wires in accordance with the principles of my present invention; and

Figure 2 is an enlarged, fragmentary view of one of said combined shroud lines and counter-

2

poise wires, with the outer covering of the line broken away to show the inner construction.

Referring now more in detail to the aforesaid preferred embodiment of my present invention, 5 with particular reference to the drawing illustrating the same, the numeral 5 designates a parachute, and the numeral 6 designates a radio transmitter.

The parachute includes a canopy 7 and a plurality of associated shroud lines 8, and the transmitter includes an antenna 9 and a counterpoise lead 10.

The shroud lines converge in the usual manner, and connect with a suitable metallic lug 11, the 15 transmitter being suspended from said lug, and having its counterpoise lead electrically connected thereto.

As best shown in Figure 2 of the drawing, each shroud line comprises a braided sheath 12, en-

20 closing a core which includes a plurality, here shown as four, of cords 13. The sheath and the cords are preferably made of an elastic material. The material chosen was a dielectric plastic adapted to withstand tensile shock by means of

25 elastic elongation. This plastic, commonly known as "nylon," belongs to the family of synthetic linear high polymers known as polyamids produced by the reaction of hexamethylene di- amine and adipic acid. Various preparations of 30 this material under some conditions exhibit elongation, within the elastic limit, of as much as 40 per cent. One of said cords has spirally wound thereon stranded copper wire 14 electrically connected to the lug 11.

35 Because of the manner in which the wire 14 is wound, the shroud lines 8 can stretch when the device is launched without danger of the wires incorporated therein snapping or becoming tangled, thereby eliminating the disadvantages 40 of the prior art as set forth in earlier portions of this specification.

This completes the description of the combination parachute and counterpoise of my present invention. Objects and advantages thereof, other 45 than those specifically referred to herein, will be apparent to those skilled in the art to which the same relates.

I claim:

1. In combination with aerial suspension means 50 having depending shroud lines for supporting a radio transmitter, an antenna counterpoise system comprising: electrical conductors spirally wound about said shroud lines and a terminal lug electrically connected to each of said conductors and to said radio transmitter.

2. In combination, aerial suspension means having shroud lines connected thereto, a radio transmitter suspended from said shroud lines below said aerial suspension means and including an antenna, said shroud lines being comprised of an elastic dielectric, and electrical conductors helically wound around certain of said shroud lines in such manner as to be jointly co-extensible therewith, and being electrically connected to said transmitter so as to form an antenna counterpoise.

3. In combination, aerial suspension means having depending shroud lines, a radio transmitter supported by said shroud lines, an antenna for said transmitter extending therefrom, said shroud lines extending laterally of said antenna and comprising elastic dielectric strands, and electrical conductors wound around certain of said strands so as to be extensible therewith, said electrical conductors being electrically connected with said transmitter and forming a counterpoise for said antenna.
